UNITED STATES PATENT OFFICE.

WILLIAM E. DAVIS, OF JERSEY CITY, NEW JERSEY.

TELEGRAPH RELAY AND SOUNDER.

SPECIFICATION forming part of Letters Patent No. 233,214, dated October 12, 1880.

Application filed July 23, 1880. (No model.)

To all whom it may concern:

Be it known that I, WILLIAM E. DAVIS, of Jersey City, in the county of Hudson and State of New Jersey, have invented a new and useful Improvement in Telegraph Relays and Sounders, of which the following is a specification.

In the drawings, Figure 1 is a plan or top view of my improved relay and sounder. Fig. 2 is a side view of the relay, partly in section, on the line xx of Fig. 1. Fig. 3 is a cross-section through the line zz of Fig. 1. Fig. 4 is a detached side view of a portion of the sounder.

My invention is of an improved form of the electro-magnet used in telegraph relays and sounders, in which novel form the magnet is arranged to act as its own armature and without any separate armature.

My invention further consists in a new mechanism for effecting the proper adjustment of the magnet in both relay and sounder, rendered necessary by the varying strength of the line-currents.

The new form of sounder and method of adjustment are used in connection with my improved form of electro-magnet and are rendered possible by its use.

Referring to the drawings, A is the relay, and B is the sounder. The relay-magnet is formed of two magnet-spools, a and b , whose cores are wrapped with wire in one circuit, so that the current, after having passed through the spool a , will traverse the spool b , the wire at Fig. 1 showing the connection of circuit. The spool a is rigidly secured to a post, j , as in Fig. 2. From this post projects a soft-iron hoop or keeper, c , which at its free end carries the spool b , so as to bring the two poles d and e of the magnets a b opposite each other in two vertical planes, and near enough to be attracted when a current is passed through the magnets a b , the elasticity of the keeper drawing the poles d and e apart when the current ceases. Both spools a b are in bodily contact with the soft-iron keeper c , whereby the magnet is completed.

The elastic keeper c is preferably adjusted by means of a screw, f , which operates, in connection with a brace or plate, g , to relax or tighten the keeper c and increase or decrease its elasticity, as may be desired.

The description so far given of the relay-magnet applies equally to the sounder-magnet, where the letters r and v represent the two spools, s the elastic keeper, t and u the poles of the magnet, and q the adjusting-screw of the keeper s .

The relay-magnet A is provided with a horizontal metal or other conducting-post, h , fastened to the vertical support j , which last is connected in the usual way, through the magnet of the sounder B, with the wire of the local battery.

Upon the keeper c of the relay-magnet, and in such manner as to be entirely insulated from it, is fastened the metal point i , which may be tipped with platinum, as may also be the post h at the point p .

The point i is connected by the wire m , through the magnet of the sounder B, with the wire of the local battery. A screw, k , presses against the prolongation l of the elastic keeper c in the relay-instrument, and as it is tightened or loosened acts to regulate the distance apart of the poles d and e ; but in the sounder there is not such a screw represented, though such a screw may be there used for the same purpose and in the same manner as in the relay.

In the sounder the prolongation of the keeper s carries a striking-pin, o , which travels or vibrates between two sounding-posts, n and n^x . (See Fig. 4.)

The motions of the pin o between the posts n n^x is so limited that the poles u and t of the magnet of the sounder B shall always be kept near enough together to be attracted when a current is passed through this magnet.

C and D are binding-screws adapted to hold the wires forming the line-circuit, and connected with the relay-magnet A in the ordinary manner, so as to bring the relay-magnet into the line-circuit—that is to say, the line-wire passes from post C to spool a , traversing the same, thence to spool b , traversing the same, thence to post D.

E and F are binding-screws adapted to hold the terminal wires running from the local battery to the sounder, and connected with the sounder-magnet B, so as to bring the sounder-magnet into the local-battery circuit—that is to say, if the sounder is in the circuit of a local battery, the wire passes from E to relay-post h ,

and from point *i*, through *m*, to spools *v* and *r*, and back to *F*, battery, or ground; but if the sounder is used in the line or main circuit and without a relay, the wire runs from *E* to *r*, 5 thence to *v*, thence to *F*.

The operation of my improved relay is as follows: When the current is transmitted from the sending-station the poles *d* and *e* of the relay-magnet are attracted and the movable 10 spool *b* of the magnet is brought nearer the fixed spool *a*, the elastic keeper *c* allowing this and being also moved. This motion of the keeper *c* brings the metal point *i* in the local circuit into contact with the point *p* of the horizontal post *h*. The keeper *c* is so regulated by the 15 screw and plate *f* *g* that any movement of the spool *b* toward the spool *a* will cause a contact of the points *i* and *p*, the point *i* moving with the spool *b*. The contact of the points *i* and *p* closes 20 the local-battery circuit already described, and as the current of the local battery passes through the spools *r* *v* the poles *u* and *t* of the sounder-magnet *B* are attracted, the movable spool *b* is drawn toward the fixed spool *r*, drawing 25 also in the same direction the elastic keeper *s*, and causing the pin *o* to strike against the stop *n* and make a sound. When the line-current is broken the poles *d* and *e* of the relay-magnet *A* no longer attract one another, the elastic 30 keeper *c* draws the spool *b* away from the spool *a* and breaks the local-battery connection by separating the points *p* and *i*. The poles *u* and *t* of the sounder-magnet then cease 35 to attract one another, the elastic keeper *s* of this magnet draws the spool *v* away from the spool *r*, and the pin *o* recedes from stop *n* and strikes stop *n*^x under the influence of the elastic keeper *s*. In this way the signals made by the Morse key at the sending-station are transmitted so as to be exactly represented by the 40 successive clicks of the pin *o* against the sounder-stops *n* and *n*^x, and are read in the familiar manner. The sounder, when used in the line-wire, is, of course, operated as described.

45 The relay-instrument above described is vir-

tually like the sounder, excepting in those particulars which always distinguish the one from the other. The relay requires the means for making and breaking the local circuit, and therefore has the parts *h* *i*, which are absent 50 in sounder. The sounder has stops *n* and *n*^x and the pin *o*, which are not in the relay.

I claim—

1. The combination of the elastic keeper *c* with the fixed spool *a* and movable spool *b*, 55 both spools being coiled with the same wire, and in line with each other to form an electro-magnet and armature combined, substantially as described.

2. In a telegraph-relay instrument, the combination of the elastic keeper *c*, fixed spool *a*, and movable spool *b*, insulated point *i* on keeper *c*, and conducting-post *h*, for closing and opening the local circuit, substantially as 60 and for the purposes described. 65

3. An electro-magnet having the two poles of its coiled spools opposite one another in two vertical planes and capable of approaching one another when the circuit is closed, substantially as specified. 70

4. The elastic keeper *c*, screw *f*, and plate *g*, in combination with the electro-magnet *a* *b*, substantially as described.

5. The combination, in a telegraph-sounder, 75 *B*, of the stops *n* *n*^x, elastic keeper *s*, having striker *o*, and magnet-spoons *a* and *b*, substantially as and for the purposes described.

6. In a telegraphic relay or sounder instrument, the electro-magnet, constructed of two spools that are attached to an elastic bar, *c*, 80 and placed in the same circuit, substantially as herein shown and described.

7. The post *j*, carrying the keeper *c*, in combination with the spools *a* *b* and screw *k*, substantially as herein shown and described.

WILLIAM ED. DAVIS.
